a corporation of Delaware

Application June 11, 1948, Serial No. 32,291

12 Claims. (Cl. 123—175)

1

This invention relates to internal combustion engines equipped with variable pitch fan blade assemblies, which are adapted to vary the volume of air supplied for engine coolant temperature control, in which the air flow can be directed toward or away from the engine radiator as required, and an object is to produce a new and improved mechanism for supplying fluid under pressure to an expansible chamber motor operatively connected to the variable pitch fan blade assembly and thermostatically regulating the pressure of the fluid delivered to the motor.

Another object is to control the operation of a variable pitch fan blade assembly by means of liquid under pressure passing axially through the engine water pump for an expansible chamber motor operatively connected to the fan blade assembly, and regulate the pressure created by such liquid.

A further object is to produce a simple and efficient mechanism for varying the pitch of a fan blade assembly for engine cooling purposes involving an expansible chamber motor operatively connected to the assembly and to which liquid under pressure is supplied coaxially through the impeller of the engine water pump.

Other objects and advantages of the invention will hereinafter appear, and for purposes of illustration but not of limitation, embodiments of the invention are shown on the accompanying drawings, in which:

Figure 1 is a fragmentary schematic view of a portion of an internal combustion engine equipped with a variable pitch fan blade assembly, a portion of the liquid cooling jacket being broken away to show the thermostatic element;

Figure 2 is an enlarged vertical sectional elevation of the variable pitch fan blade assembly, expansible chamber motor, engine water pump and associated parts;

Figure 3 is a sectional view substantially on the line 3—3 of Figure 2;

Figure 4 is an enlarged sectional view showing the thermally responsive fluid pressure regulating mechanism; and

Figure 5 is a fragmentary sectional view showing an alternate form in which the water pump impeller is disposed within the engine block.

The illustrated embodiment of the invention shown on Figures 1 to 4 comprises an internal combustion engine 10 having a water cooling jacket 11 through which liquid, such as water, is adapted to be forced by a pump having a casing 12 suitably connected to an end wall of the engine 10. Within the casing is a rotary impeller 55

2

43 of the blade type for causing liquid circulation through the engine jacket. Tubes 14 and 15 lead from opposite portions of the pump casing and communicate with the upper and lower portions 5 of the engine cooling jacket as will be readily understood.

Secured in any suitable manner to the front end of the pump casing 12 and forming a wall thereof is a bearing housing 16 having a water pump filler opening 16a closed by a plug 16b. Mounted within the housing 16 is a shaft 17, an intermediate portion of which is supported by a ball bearing unit 18. On the forward end of the shaft is keyed the hub of a drive sheave 19, which 10 is suitably grooved to receive V belts 20. The belts 20 are also connected to sheaves (not shown) driven in any suitable manner by the internal combustion engine 10. Interposed between the hub of the sheave 19 and the forward 15 end portion of the bearing housing 16 is a ball bearing unit 21, a spacer sleeve 22 being interposed between the ball bearing units 18 and 21. It will be observed that the right-hand portion (Figure 2) of the sheave 19 is recessed to receive the end portion of the bearing housing 16 to economize on space and compact the assembly.

The forward or left-hand face (Figure 2) of the sheave 19 is cupped to provide a chamber 23 for the expansible chamber motor, and forming an end wall for the chamber 23 is a diaphragm 24 of rubber-like material, the edge portions of which are securely held between a pair of metallic rings 25, the central portions of which are ribbed as indicated at 26, securely to hold the diaphragm in place. An end member 27 is suitably secured, as by bolts, to the sheave 19 thereby rigidly to anchor the peripheral portion of the diaphragm in place and form a liquid-tight joint. Preferably the end member 27 is in two sections suitably bolted together to retain therebetween the variable pitch fan blade assembly, generally indicated at 28. The specific structure of the fan blade assembly forms no part of the present invention and reference is hereby made to the patent to Earley et al. No. 2,437,810, dated March 16, 1948, for a more complete description of the structure and operation. Suffice it to say that a plurality of fan blades 29 is provided and each fan blade has a stub shaft rotating in a ball bearing unit 31. Engaging the inner end of the ball bearing unit 31 is a nut 32 and pinned to the reduced end of the stub shaft 30 is a disc 33 having an eccentrically positioned actuating pin 34, which engages in a shoe 35. The shoe 35 seats in a groove in a carrier 36 which

is secured, as by welding, to a cup 37 which is secured to the central portion of the diaphragm 24, a lug 38 passing through an aperture in the center of the diaphragm and a plate 39 being secured to the opposite side of the diaphragm. The lug is upset to secure the plate 39 in clamping relation. The arrangement is such that movement of the cup 37 to the left of Figure 2 imparts conjoint movement to the several fan blades 29, and movement of the cup in the opposite direction is effected by a conical spring 40, which bears at one end against the carrier 36 and at the opposite end against a plate 41, suitably fixed as by bolts to the outer face of the end member 27.

Preferably the fan blades 29 are counter-weighted so that they are constantly urged into maximum pitch. Accordingly in the event of failure in the operation of the mechanism for varying the fan blade pitch, the blades will be in maximum pitch to supply cooling air to the internal combustion engine.

A nut 42 on the end portion of the shaft 17 clamps a washer 43 against the outer surface of the hub of the sheave 19 and the water pump impeller 13 is fixed to the opposite end of the shaft 17 for rotation therewith. The shaft 17 is provided with a longitudinally extending, axially disposed conduit 44 which opens at its left-hand end (Figure 2) into the chamber 23, the opposite end communicating with a lateral passage 45 to which a tube 46 is connected. As will hereinafter appear, liquid under pressure from the tube 46 passes through the lateral passage 45 into the bolt conduit or passage 44 and thence into the chamber 23 to exert pressure against the diaphragm 24 for varying the pitch of the fan blades 29. It will be apparent that the right-hand end portion (Figure 2) of the shaft 17 extends into the water pump casing 12. Accordingly, it is necessary to effect a liquid seal between opposite sides of the hub of the water pump impeller 13 and the water pump casing on the one hand, and the bearing housing 16 on the other hand. This is accomplished by a fluid seal 47.

The structure of the fluid seal 47 is as follows: A metallic ring 48 is secured to the bearing housing 16 and surrounds the shaft 17. Bearing against the flat outer face of the ring 48 is a carbon ring 49 which has an outwardly projecting relatively narrow rib in sliding contact with the ring 48. A rubber bellows 50 is connected at one end to the opposite face of the carbon ring 49 and has its opposite end bonded to a metal cage 51, which is flanged to provide a seat for one end of a coil spring 52, the opposite end of which bears against the hub of the water pump impeller 13. The pressure of the fluid on opposite sides cooperates with the above parts effectively to prevent the water from within the water pump casing 12 and liquid, such as oil, for the passage 44, from intermingling. Adjacent the fluid seal is a drain cavity 53.

A similar fluid seal 54 is interposed between the opposite face of the hub of the pump impeller 13 and the adjacent portion of the casing 12, this seal also employing a similar carbon ring 55 which is spring-urged against a metal ring 56 by a coil spring, a rubber bellows and metallic cage being similarly employed.

Intermediate the metallic ring 56 and adjacent wall of the casing 12 is a rubber ring 57, which is forced into fluid-tight sealing engagement by the pressure exerted by the carbon ring

55 through the ring 56. It will also appear in this form of the fluid seal that a rubber ring 58 is urged by the metallic cage against the impeller hub effectively to seal that region. Fluid-tight seals of the above character are available on the market and their detail construction and operation are well-known to those skilled in this art, so that further description thereof is not deemed necessary.

10 The tube 46 may lead to the engine oil pump (not shown) so that oil under pressure is normally forced through the tube 46 and into the chamber 23 for actuating the expansible chamber motor. As will hereinafter appear, the pressure of oil delivered to the expansible chamber 15 motor is thermostatically controlled as, for example, in accordance with the temperature of the water or other liquid in the engine cooling system. In this manner, when the engine is 20 relatively cold, the fan blades 29 may be disposed at zero, minimum or reverse pitch, thus reducing or shutting off the air supplied for engine coolant temperature control. As the temperature of the liquid in the engine cooling jacket increases so that cooling action of the fan is desired, then the oil pressure is utilized automatically to vary the pitch of the fan blades gradually to increase the volume of air supplied for engine cooling purposes.

30 As shown, a valve housing 59 interposed in the tube line 46 is attached to the engine cooling jacket 10. As shown in Figure 4, a thermostat 60 extends well inside the engine jacket 11 and is responsive to the temperature of the liquid in the engine cooling system. The thermostat 60 is carried by a fitting 61, which is screwed into an aperture in the engine jacket. Suitably connected for actuation by the thermostat 60 is a rod 62 which has a reduced extension 63 providing a shoulder against which a flanged washer 64 abuts. Thermostats suitable for this purpose are commercially available and involve the use of materials sensitive to temperature variations for effecting positive to and fro movement of the rod 62, increase of temperature causing the rod 62 to move upwardly (Figure 4) and reduction in temperature causing the rod to move downwardly.

Connected to a side of the valve casing 59 is a tube 65, which leads to the engine crank case (not shown) or other suitable reservoir. Having one end seated against the flanged washer 64 is a coil spring 66, the opposite end of which engages a shoulder on a piston type valve member 67 slidable on the reduced extension 63, a pin 68 limiting the outward movement of the valve 67. In the normal position, the valve 67 engages a ported ring 69. A relatively stronger coil spring 70 seats at one end against a disc 71 which engages a shoulder 72 on the rod 62 and the opposite end engages a ring 73 which abuts against a shoulder on the valve casing. When the rod 62 moves upwardly, it first compresses the coil spring 70 but after the valve 67 engages its seat 74, further movement of the rod 62 will additionally compress the lighter spring 66. When the temperature of the cooling liquid decreases, the coil springs 70 and 66 successively operate to unseat the valve, as will be readily apparent.

In operation, when the engine is cold, liquid from the oil pump will be forced through the valve casing 59, the ported ring 69 and to the reservoir or crank case through the tube 65. When the temperature of the engine cooling liquid increases, a pressure differential is created by the 75 closing or partial closing of the valve 67 so that

higher fluid pressures are built up in the chamber 23 for actuating the diaphragm 24 to increase the pitch of the fan blade. Thus the operation of the expansible chamber motor is controlled by the position of the valve 67 which in turn is actuated in response to changes in the engine temperature. The higher the temperature of the engine, the greater is the restriction in the flow of oil back to the reservoir or crank case, and accordingly, the greater will be the pressure developed in the expansible chamber motor against the flexible diaphragm 24. Thus a portion or all of the oil may be by-passed to the reservoir or crank case through the tube 65, or all of the pressure generated by the oil pump may be utilized in actuating the diaphragm 24 against the tension of the coil spring 40. In this manner, the pitch of the several fan blades is smoothly and automatically varied in accordance with the temperature requirements of the engine.

An important feature of this invention resides in the manner in which liquid is delivered to the expansible chamber motor, as shown, the liquid being passed coaxially of the water pump impeller directly to the expansible chamber motor. The fluid sealing of the pump impeller to militate against the oil entering the pump casing and on the other hand, preventing water from entering the oil stream, is of importance in effecting an exceedingly compact and efficient design.

The form of the invention shown on Figure 5 is similar to that above described, except that the water pump impeller 13a is disposed within the engine cooling jacket 11a, a fluid seal 54a being interposed between the hub of the impeller 13a and a bearing housing 16' which abuts against and is suitably secured to the engine block. In this instance, the tube 46 delivering oil under pressure to a lateral passage 45a in the bearing housing 16' registers recurrently with a lateral passage in the driven shaft 17a which communicates with an axial passage 44a. A fluid seal 47a on the opposite side of the passage 45a effectively seals the adjacent portion of the shaft against liquid.

It is to be understood that numerous changes in details of construction, arrangement and operation may be effected without departing from the spirit of the invention especially as defined in the appended claims. The thermally responsive unit may be located differently than above described, as, for example, it may be responsive to the lubricating oil temperature, other parts of the engine, or to the air temperature.

What I claim is:

1. In an internal combustion engine equipped with a variable pitch fan blade assembly to supply air for engine cooling purposes, means responsive to the engine temperature for varying the pitch of the fan blades, said means comprising an expansible chamber motor having a movable wall operatively connected to the fan blade assembly, a water pump for the engine having an impeller coaxial with the fan blade assembly, a source of fluid under pressure in communication with said chamber through the axis of said impeller to actuate said motor, and valve means for regulating the pressure of the fluid in said chamber.

2. In an internal combustion engine equipped with a variable pitch fan blade assembly to supply air for engine cooling purposes, means responsive to the engine temperature for varying the pitch of the fan blades, said means comprising

an expansible chamber motor having a movable wall operatively connected to the fan blade assembly, a water pump for the engine, said water pump and expansible chamber motor being disposed between the fan blade assembly and the engine, and means for supplying fluid under pressure through the water pump to said motor to actuate same, and valve means for regulating the pressure of the fluid supplied to said motor.

3. The organization as claimed in claim 2, in which the water pump, fan blade assembly and expansible chamber motor are coaxially arranged, and the fluid supplying means includes a conduit leading to the motor disposed coaxially of said water pump.

4. In an internal combustion engine equipped with a variable pitch fan blade assembly to supply air for engine cooling purposes, means responsive to the engine temperature for varying the pitch of the fan blades, said means comprising an expansible chamber motor having a movable wall operatively connected to the fan blade assembly, a drive for the fan blade assembly having a portion cooperating with the movable wall

25 to form the chamber for the expansible chamber motor, a liquid cooling pump for the engine having a rotary impeller, a shaft coaxial with said drive and impeller and secured for rotation thereto, said shaft having a longitudinal passage opening into the chamber of said expansible chamber motor, a source of fluid under pressure in communication with said chamber through said passage, and means for regulating the pressure of fluid in said chamber.

5. The organization as claimed in claim 4, in which the shaft passage extends therethrough from end to end, and fluid sealing means for sealing the pump impeller for militating against intermingling of the cooling liquid and pressure fluid.

6. The organization as claimed in claim 4, in which the regulating means comprises a valve thermostatically responsive to the temperature of the engine cooling liquid.

7. The organization as claimed in claim 4, in which the regulating means comprises a by-pass for the fluid under pressure, valve means to control the flow of fluid through said by-pass, and thermostatic means responsive to the engine temperature for actuating said valve means.

8. In an internal combustion engine equipped with a variable pitch fan blade assembly to supply air for engine cooling purposes, means responsive to the engine temperature for varying the pitch of the fan blades, said means comprising an expansible chamber motor having a movable wall operatively connected to the fan blade assembly, a drive for the fan blade assembly having a portion cooperating with the movable wall 55 to form the chamber for the expansible chamber motor, a support carried by the engine for said motor, fan blade assembly and drive, a source of fluid pressure in communication with said chamber and including fluid passage means in said support, and valve means thermostatically responsive to the engine temperature for regulating the pressure of fluid in said chamber.

9. In an internal combustion engine equipped with a variable pitch fan blade assembly to supply air for engine cooling purposes, means responsive to the engine temperature for varying the pitch of the fan blades, said means comprising an expansible chamber motor having a movable wall operatively connected to the fan blade assembly, a water pump for the engine, said water

pump and expansible chamber motor being disposed between the fan blade assembly and the engine, means for supplying engine lubricating oil under pressure through the water pump to said motor to actuate same, and valve means for regulating the pressure of the lubricating oil supplied to said motor.

10. In an internal combustion engine equipped with a variable pitch fan blade assembly to supply air for engine cooling purposes, means responsive to the engine temperature for varying the pitch of the fan blades, said means comprising an expansible chamber motor having a movable wall operatively connected to the fan blade assembly, a water pump for the engine having an impeller coaxial with the fan blade assembly, means for supplying engine lubricating oil under pressure through the axis of said impeller to actuate said motor and valve means thermostatically responsive to the engine temperature for regulating the pressure of the lubricating oil in said chamber.

11. In an internal combustion engine equipped with a variable pitch fan blade assembly to supply air for engine cooling purposes, means re-

5 sponsive to the engine temperature for varying the pitch of the fan blades, said means comprising an expansible chamber motor having a movable wall operatively connected to the fan blade assembly, a drive for the fan blade assembly having a portion cooperating with the movable wall to form the chamber for the expansible chamber motor, a source of fluid pressure in communication with said chamber, and 10 valve means for regulating the fluid in said chamber.

12. The organization as claimed in claim 11, in which the drive for the fan blade comprises a pulley axially recessed to cooperate with the movable wall to provide the motor chamber.
